Specification of Letters Patent. Patented Sept. 15, 1914.

Application filed November 25, 1912. Serial No. 733,299.

To all whom it may concern:

Be it known that we, BENJAMIN H. BECKER and JOHN CIESLA, both citizens of the United States, residing in Chicago, county of Cook, and State of Illinois, have invented certain new and useful Improvements in Soap-Presses, of which the following is a specification.

Our invention relates to improvements in that class of presses which are used in the final steps of the manufacture of soap in cake form to give the blank cake its final or finished form and impress thereon characters indicating its source of manufacture, brand, etc.

The machine of our present invention is in the nature of an improvement upon a machine of similar character forming the subject matter of a Patent No. 1,085,236, granted to us January 27, 1914, and among the principal objects of the present invention are, to provide an improved feed mechanism for the blanks, to provide an improved delivery mechanism for the finished cakes, both of which mechanisms shall be readily adjustable to accommodate the handling of blanks and cakes of different sizes, and to provide a machine of superior efficiency and capable of operating at a higher speed than has heretofore been possible in machines of this class.

The machine of our invention, its mode of operation, and the advantages which are attained thereby, will all be readily understood when considered in connection with the following detail description and the accompanying drawings, in which latter—

Figure 1 is a front elevational view. Fig. 2 is a side elevation, with parts omitted from the feeding-in side of the machine, showing the blank-feeding conveyer and main pusher in cross-section. Fig. 3 is a top plan view, partially broken out. Fig. 4 is an enlarged detail top plan view of the platform of the machine, showing the blank-feeding mechanism, the matrix, the blank-centering mechanism, and the adjustable auxiliary discharge conveyer. Fig. 5 is a side elevation of the parts shown in Fig. 4. Figs. 6 and 7 are detail side and edge views, respectively, of a portion of a lever that ac-

tuates the cross-feed pusher, and is provided with a frangible joint adapted to yield to avoid breakage, in the event of an obstruction to the pusher. Fig. 8 is a fragmentary side elevation of a portion of a connecting rod, forming a part of the operating mechanism of the longitudinal pusher and also provided with a frangible joint. Fig. 9 is a cross-section on the line 9—9 of Fig. 8. Figs. 10 and 11 are detail views of parts of the tripping mechanism of the lower die member, showing two different positions of the same.

Referring to the drawings, 5 designates each of a pair of skeleton side-frame members rigidly connected at their upper ends by a table or platform 6, on which latter is secured a die-box or matrix 7. Rigidly bolted to the table 6 is a pair of parallel upright frame members 8, best shown in Fig. 2, the forwardly projecting ends of which form a vertical slide-way 9, in which is reciprocably mounted a cross-head 10, to the lower end of which is secured the upper die block 11. Within the cross-head 10 is a pair of upper and lower springs 12 and 13, respectively, between which is clamped the forwardly projecting end of a rocking-beam 14, this latter being pivoted at 15 between the uprights 8. Journaled in rearwardly extending brackets 16 of the main frame and in a pedestal 17 is the main driving shaft 18, on which is an eccentric 19 connected by an eccentric-strap 20 and connecting-rod 21 to the lower end of the rocking-beam 14, for actuating the latter and the cross-heads 10.

22 designates the lower die member located within the matrix 7, and secured on the upper end of a stem 23 that is slidably mounted in a bushing 24 secured to the under side of the table 6. Fast on the stem 23 is a tappet 25 having a squared lower end and a tapered or beveled upper end 25'. The lower end of the stem 23 of the lower die member is guidably supported in a bearing sleeve 26 secured to a cross-bar 27 of the main frame.

The lower die member 22 is raised to carry the compressed cake out of the matrix 7 and to a position to be ejected from above

the matrix, by mechanism connected to and actuated from the cross-head 10 and engaging the tappet 25. This mechanism comprises an arm 28 rigidly bolted to the upper end of the cross-head 10, a vertical rod 29 adjustably connected to the arm 28 by a collar 30 on said arm and a set screw 31, said rod 29 extending through and having a bearing in the table 6 and an underlying bearing-sleeve 32, and a tappet-arm 33 pivotally mounted on the rod 29 near the lower end of the latter. The free end of the arm 33 is normally urged toward the die-stem 23 by a spring 34 connected at one end to the arm 33 and at its other end to a bracket 35 secured to the lower end of the rod 29. It will thus be seen that the lifter rod 29 is positively actuated in both directions by and from the cross-head 10. As the cross-head approaches the limit of its downward movement, the free end of the arm 33 slides over the bevel top 25' of the tappet 25 and engages the latter from beneath, and as the cross-head rises, the arm 33 rises, raising the tappet, the stem 23, and the lower die member 22 for the elevation of the pressed blank out of the die-box. As soon as this has been accomplished, the arm 33 is disengaged from beneath the tappet 25 by means of a revolving segment-plate 36 (Figs. 10 and 11) that is fast on a cross-shaft 37 of the machine, and, at the proper time in each revolution, sweeps past an inclined wiper-finger 38 carried on the outer end of an arm 39 that is fast with the hub of the arm 33. Fig. 10 illustrates the position of the parts just before the segment-plate has engaged the wiper-finger, and Fig. 11 illustrates the laterally offset position of the wiper-finger and its arm as the segment-plate sweeps past the same. This allows the lower die-box, its stem, and the tappet 25 to drop by gravity, to prepare the die-box for the reception of the next blank. The fall of the lower die member and its stem is cushioned by reason of the engagement of an arm 40 on the lower end of the die-stem 23 with the upper arm of a lever 41 that is pivoted on a cross-rod 42 of the machine frame and the other arm of which is connected to the upper end of a tension spring 43 anchored at 44 to a cross-bar 44' of the frame. The cross-shaft 37 carrying the segment-plate 36 is driven from the main shaft 18 by intermeshing bevel gears 45 and 46 on shafts 37 and 18, respectively. Adjustably mounted in the arm 40 is a post 40', the upper end of which, when the die-stem 23 is in raised position, lies in the path of a striker 36' secured to one side of the revolving segment-plate 36. Normally the post 40' drops, with each descent of the die-stem 23, out of the path of the striker 36'; but in case the lower die-member 22 sticks, when raised, in the matrix, as occa-

sionally happens, the striker 36' engages the head of the post 40' and by a quick blow forces the die-stem and die down to the lower position.

Referring now to the mechanism for feeding the blanks to the die-box for compression between the upper and lower die members, 47 designates an endless conveyer-belt that is mounted horizontally at the left side of the machine, the upper or blank-carrying lap of said belt running between lateral guides 48 that are so mounted, by means of slotted fastening brackets 49 and clamp screws 50, as to be adjustable toward and from each other to accommodate blanks of different widths; a line of such blanks being indicated at 51 in Fig. 3. Mounted on a slide-way 52 alongside and parallel with the feeding-in conveyer 47 is a cross-head 53, to which is connected the stem 54 of the main longitudinal pusher, the head 55 of which slides over an auxiliary platform 56 that is flush with the upper lap of the conveyer-belt 47 and with the upper end of the die-box 7. The longitudinal pusher is reciprocated from the cross-shaft 37 by means of a crank-arm 57 on the free end of said shaft, a connecting-rod 58, a lever 59 fulcrumed at 60 to a bracket 61 on one of the side-frame members 5, a link 62, and a depending arm 63 on the cross-head 53, as clearly shown in Fig. 1. In order to prevent possible injury to the actuating mechanism of the longitudinal pusher through accidental jamming of the blanks, we so construct this operating mechanism as to make it yieldable in such an event, and the frangible joint which affords this yieldable feature we preferably locate in the connecting-rod 58. Referring to the detail views, Figs. 8 and 9, it will be noted that said rod is made in two aligned sections 58^a and 58^b. The latter section has a longitudinal split 64 extending some distance inwardly of its meeting end, and also a groove 65 formed in one side thereof opposite said split; while the section 58^a has secured thereto a tongue 66 that lies within the groove 65, and is frictionally secured within said groove by a clamp 67. This frictional connection is sufficient to maintain the two sections of the connecting-rod 58 in working relation under the normal operation of the machine; but in the event of accidental jamming of the blanks so as to prevent the full forward movement of the pusher-head, the sections of the connecting-rod will yield, and so avoid breakage of the parts.

On the auxiliary platform 56 is mounted a combined guide and stop consisting of two vertical walls 68 and 69, the former of which extends across the inner end of the conveyer-belt 47, and part way across the platform 56, the latter of which extends at right angles to the wall 68 toward the die-box. The wall

68 forms a stop for the blanks 51 as they are fed forward by the conveyer-belt 47, and also a guide for directing the travel of the foremost blank to a position directly in front of the pusher-head 55, and the wall 69 forms one lateral guide for the subsequent travel of the blank to a position directly over the die-box. As best shown in the detail view, Fig. 4, the guide-walls 68, 69, are rendered adjustable width-wise of both the cross-passage 70 and the longitudinal passage 71 through which the pusher-head 55 operates by a fastening-bracket 72 having transverse slots 73 and fastening-screws 74 securing the same to underlying supports 75, and longitudinal slots 76 and fastening-screws 77, securing said guiding and stop member thereto. The other side of the cross-passage 70 is formed by a wall 78, and the other side of the longitudinal passage 71 is formed by a wall 79 that is adjustable laterally by transverse slots 80 and fastening-screws 81. The inner end of the feeding-in belt 47, the cross-passage 70, and the longitudinal passage 71 are preferably overlaid by a cover-plate 82 to prevent accidental upright displacement of a blank traveling through the passages 70 and 71. Reciprocably mounted in supports 83 carried by the table 6 is the stem 84 of a cross-pusher, the head of which is indicated at 85. The pusher-head 85 reciprocates across the inner end of the feeding-in belt 47 and through the cross-passage 70, and operates to successively force the blanks from the conveyer-belt across and into the path of movement of the longitudinal pusher-head 55. The actuating mechanism of the cross-pusher is best shown in Fig. 2 and comprises a grooved cam 86 fast on the cross-shaft 37, a lever 87 pivoted to the frame at 88 and having a pin 89 engaging the groove of the cam, and a link 90 connecting the upper end of said lever with the pusher-stem 84. The pusher-stem 84 is formed flush with one vertical edge of the pusher-head 85, and forms a temporary stop or abutment for each blank while the immediately preceding blank is being forced by the pusher-head across into the path of the longitudinal pusher-head 55. As soon as the pusher-head 85 retreats to the position shown in Fig. 4, the blank held back thereby immediately advances into engagement with the stop-plate 68 and in position to be engaged and advanced by the next forward movement of the cross-pusher.

In the driving mechanism of the cross-pusher we provide a frangible joint safety device of the same general nature and for the same purpose as that provided in the operating mechanism of the longitudinal pusher. This device, which is shown in the detail views, Figs. 6 and 7, is formed in the lever 87, which latter is made in two longitudinally aligned sections 87^a and 87^b. The

meeting ends of these sections are connected by a pair of splints 91 secured thereto by upper and lower cross-bolts 92 and 93, respectively, and said meeting ends are formed with an articulated joint 94 permitting relative angular swing thereof. The tendency to bend at the joint is resisted by a pair of stiff leaf-springs 95 secured to the edges of the upper section 87^a and overlapping the edges of the lower section 87^b; and said sections are further rigidly connected by small cross-pins 96 and 97 which, under undue strain, will shear and thus permit the joint to yield.

In Figs. 4 and 5 we show a mechanism for arresting and accurately centering each blank as it is forced by the pusher-head 55 to a position directly over the matrix and between the upper and lower die memoers. 98 designates each of a pair of arms having vertical hubs 99 by which they are mounted on pivot studs 100 carried by blocks 101 that are adjustably secured on a cross-shaft 102. The inner sides of the arms 98 are provided with non-metallic facing-blocks or pads, 90 preferably of rubber, and indicated at 103. The arms 98 have outwardly turned extensions 98', to the free ends of which are secured depending downwardly and outwardly inclined cam-plates 104. The centering arms are normally urged inwardly or toward each other across the upper side of the matrix by means of tension springs 105 secured at one end to rearwardly and outwardly extending arms 106 on the hubs 99, 100 and anchored at their other ends to screws 107 mounted in fixed brackets 108 on the machine frame. The inward swing of the centering arms is adjusted and limited, according to the width of the blank operated upon, 105 by adjustable stops in the form of screws 109 passed through depending lugs 110 on the arms 98 and adapted, at their inner ends, to engage the outer side walls of the matrix 7.

The means for spreading the centering arms in order to release the blank at the instant of its engagement by the die member comprises a rock-shaft 111 journaled in a bracket 112 and a supporting block 127 hereafter referred to, and having keyed thereon a pair of inwardly and upwardly inclined cam-arms 113 that coöperate with the cam-plates 104, the upward swing of said arms causing the latter to engage the 120 inclined surfaces of the cam-plates, thus spreading the centering arms 98 in opposition to the spring 105, and the downward swing of said arms permitting the centering arms 98 to approach each other under the 125 impulse of said springs. The rock-shaft 111 is oscillated from the vertically reciprocating rod 29 by means of connections therebetween comprising a collar 114 (Fig. 1) keyed to the lower end of the rod 29, a lever 130

115 having a pin-and-slot connection 116 with said collar at one end and a pivotal connection 117 at its other end with the frame, an upwardly extending connecting link 118 pivotally connected at its lower end to the lever 115, and an arm 119 (Fig. 4) fast on the rock-shaft 111 and pivotally connected to the upper end of link 118. From this it will be apparent that the downward movement of rod 29 will actuate the rock-shaft 111 in a direction to spread the centering arms, while the opposite movement of the rod 29 will lower the cam-arms 113 and permit the inward or closing movement of the centering arms.

120 and 121 designate a pair of rods mounted in brackets 122 and 123, respectively, secured to the frame of the machine, the rod 120 overlying the forward extension 98' of one of the centering arms, and the rod 121 underlying the rearward extension 106 of the other centering arm. The purpose of these rods is to resist the upward thrust on the centering arms caused by the action of the cams 113, and prevent undue wear and looseness at the vertical pivot joints 100 of the centering arms.

The blank arresting and centering mechanisms last described is not claimed herein, 30 but forms in part the subject-matter of our application Serial No. 675,142, before referred to.

124 (Fig. 1) designates an endless conveyer-belt suitably mounted on the opposite side of the matrix from the feeding-in mechanism to effect the delivery from the machine of the shaped and stamped cakes of soap. The inner end of the discharge conveyer 124 is mounted on a drum 125 that 40 is journaled between supporting brackets 126 rigid with the side frame 5. In order to bridge the space between the inner end of the main discharge conveyer 124 and the matrix, we provide a short auxiliary discharge conveyer which is so constructed and mounted as to be capable of a limited adjustment bodily in the direction of its length so as to serve matrices of different sizes forming cakes of different lengths.

50 127 designates a supporting block secured to the table 6 and formed in its opposite sides with grooves 128 in which are mounted narrow plates 129, in and between the outer ends of which are journaled rolls 130, over 55 which is trained the endless auxiliary conveyer-belt 131. The plates 129 are formed with longitudinal slots 132, through which and through holes in the block 127 are passed clamping bolts 133. By reason of 60 this construction it will be readily seen that the auxiliary conveyer-belt and its supports can be adjusted longitudinally to coöperate with matrices of different lengths; the mechanism as shown being set for coöperation 65 with the largest size matrix employed in the

machine. To the upper side of the block 127, on opposite sides of the upper section of the conveyer-belt are secured by screws 134 horizontal strips 135, to which latter are secured by angle brackets 136 vertical 70 guide walls 137; the feet of the angle bracket 136 being slotted, as shown at 138 to receive fastening screws 139, by which the guide walls 137 may be bodily adjusted laterally. The rear ends of the strips 135 are connected by a narrow bridge piece 140 that overlies the forward end of the main conveyer 124, as clearly shown in Fig. 1.

In the operation of the machine, the rectangular blanks are supplied to the outer 80 end of the feeding-in conveyer 47 by the attendant, and by said conveyer are carried in close juxtaposition inwardly of the machine. As soon as the foremost blank engages the stop and guide wall 68 it is engaged laterally by the head 85 of the cross-pusher and forced sidewise through the cross-passage 70 formed by the platform 56 and the walls 68 and 78 into the path of the main longitudinal pusher-head 55 which, at this instant, is 90 fully retracted. During this movement of the cross-pusher, its stem 84 forms a temporary stop for the line of blanks, and as soon as the cross-pusher is fully retracted, the next foremost blank moves into position 95 to be operated upon by the cross-pusher. While this is taking place, the forward movement of the main pusher 55 advances the first blank to a position directly over the matrix where it is accurately centered and 100 lightly held by the friction faces 103 of the centering arms 98 (Fig. 4). The centered blank is then engaged by the upper die member 11 and is compressed and stamped within the matrix. On the rise of the upper 105 die member, the stamped cake is lifted out of the matrix by the lower die member, and is at that instant pushed forward by the next advancing blank onto the auxiliary 110 conveyer 131, by which it is transferred to the main delivery conveyer 124; the finished cakes being removed from the latter by attendants for wrapping and packing.

To adapt a machine to the handling of larger or smaller blanks, the side walls of 115 the guide passages are adjusted to accommodate the new size, the proper sized matrix is substituted, the centering arms are adjusted, and the auxiliary conveyer is bodily adjusted as may be necessary to place it in 120 coöoperative relation with the new matrix. These adjustments require but a small amount of time and labor, and give the machine a capacity for handling quite a variety of sizes and shapes of soap. With the 125 various coöoperating parts accurately adjusted and timed, the machine is capable of operating reliably at a high speed without jamming or producing imperfect specimens of the product. It will be manifest to those 130

skilled in the art that the novel features specified in the claims hereunto appended may be varied somewhat in detail from the forms thereof herein illustrated without involving any departure from the substance 5 of the invention or the principles of operation underlying the same.

We claim—

1. In a soap-press, the combination of a 10 matrix, and a lower die-member having a depending stem, of means for raising said lower die-member to eject a stamped cake from said matrix and allowing it to fall, means for cushioning the fall of said lower 15 die-member, and means for positively forcing said die-member downwardly in the event of its failure to fall.

2. In a soap-press, the combination of a 20 matrix-pocket, an upper die, a reciprocatory stem carrying said upper die, a reciprocatory member adapted to operate said stem, a spring interposed between said reciprocatory member and said stem, a lower die in said pocket, a reciprocatory stem for said lower 25 die, operative connections between said reciprocatory stem and said reciprocatory member for raising said lower die in said pocket, and release mechanism permitting the lower die to drop in said pocket.

3. In a soap-press, the combination of a 30 matrix-pocket, an upper die, a reciprocatory stem carrying said upper die, a reciprocatory member adapted to operate said stem, a spring interposed between said reciprocatory member and said stem, a lower die in said pocket, a reciprocatory stem for said lower die, a reciprocatory rod operatively connected to said reciprocatory member, an arm on said rod adapted to engage a projection 35 on said lower stem and raise said lower die, and release mechanism synchronized with said reciprocatory member and adapted to disengage the arm from said projection.

4. In a soap-press, the combination of a 45 matrix-pocket, an upper die, a reciprocatory stem carrying said upper die, a reciprocatory member adapted to operate said stem, a spring interposed between said reciprocatory member and said stem, a lower die in 50 said pocket, a reciprocatory stem for said lower die, a reciprocatory rod operatively connected to said reciprocatory member, an arm on said rod adapted to engage a projection on said lower stem and raise said lower 55 die, a spring tending to force said arm into engagement with the projection on said stem, and cam mechanism synchronized with said reciprocatory member and adapted to move said arm against the pull of said 60 spring to disengage said projection and permit said lower stem to return to normal.

5. In a soap-press, the combination of a 65 matrix-pocket, a lower die member in said pocket and having a depending stem, means for raising said die member and stem to

eject the cake of soap therefrom, means for disengaging said raising means from said stem, and means for forcing said stem down to its normal position in said pocket in the event of its failure to fall.

6. In a soap-press, the combination with a 70 matrix and a pair of die-members adapted to receive and stamp a blank, of a blank-feeding and delivery mechanism comprising a horizontal endless belt conveyer for feeding the blanks, a delivery-conveyer on one side of and in line with said matrix, a reciprocatory main pusher on the other side of said matrix in line therewith, in line with said delivery-conveyer and alongside of and parallel with said feeding-conveyer, and adapted to push the blank into the field of said matrix and to push the completed cake into engagement with said delivery-conveyer, and means for conveying the blank 80 from said feeding-conveyer to the field of said pusher.

7. In a soap-press, the combination with a 85 matrix and a pair of die-members adapted to receive and stamp a blank, of a blank-feeding and delivering mechanism comprising a horizontal endless belt conveyer for feeding the blanks, a delivery-conveyer on one side of and in line with said matrix, a reciprocatory main pusher on the other side 90 of said matrix in line therewith, in line with said delivery-conveyer and alongside of and parallel with said feeding-conveyer, and adapted to push the blank into the field of said matrix and to push the completed cake 95 into engagement with said delivery-conveyer, and a reciprocatory cross-pusher for conveying the blank from said feeding-conveyer to the field of said main pusher.

8. In a soap-press, the combination with a 100 matrix and a pair of die-members adapted to receive and stamp a blank, of a blank-feeding and delivering mechanism comprising a horizontal endless belt conveyer for feeding the blanks, a horizontal endless belt conveyer for delivering the blanks located on one side of said matrix, a reciprocatory main pusher alongside of and parallel with said feeding conveyer and located in line with and on the other side of said matrix 105 and adapted to push the blank into register with said matrix and to push the completed cake therefrom into the field of said delivery-conveyer, and a reciprocating cross-pusher adapted to push the blank from said feeding-conveyer into the field of said main pusher.

9. In a soap-press, the combination with a 115 matrix and a pair of die-members adapted to receive and stamp a blank, of a blank-feeding and delivering mechanism comprising a horizontal endless belt conveyer for feeding the blanks, an endless belt conveyer on one side of, in line with said matrix and parallel with said feeding-conveyer, a recip- 120

rotatory main pusher alongside of and parallel with said feeding-conveyer and located in line with and on the other side of said matrix and adapted to push the blank into register with said matrix and to push the completed cake therefrom into the field of said delivery-conveyer, and a reciprocating cross-pusher adapted to push the blank

from said feeding-conveyer into the field of said main pusher.
